INTERNAL COMBUSTION ENGINE

Andre J. Meyer, Detroit, Mich., assignor to Continental Motors Corporation, Detroit, Mich., a corporation of Virginia

Application January 20, 1930, Serial No. 421,998

11 Claims. (Cl. 123—53)

My invention is related to internal combustion engines and is more particularly related to means for effecting an internal cooling of the cylinders supplementing the usual external cooling thereof.

5 It is the object of my invention to increase engine efficiency by providing means for increasing the compression ratio of an internal combustion engine.

Another object of my invention is to construct 10 an internal combustion engine having a relatively higher ratio of compression by providing means for supplementing the usual external cooling means to further reduce the temperature of the engine cylinders, thereby permitting an increase 15 in the compression ratio without the danger of preigniting the compressed gases.

Another object of my invention is to effect an increased cooling of the engine with a resulting 20 increase in engine efficiency by supplementing the external cooling means usually employed for internal combustion engines with an additional means for internally cooling the engine cylinders at periodical intervals.

A further object of my invention is to effect 25 a supplementary internal cooling of the cylinders of an internal combustion engine, by periodically admitting a charge of air into said cylinders and providing means for effecting a heat transfer between the products of combustion and the air, thereby effecting a cooling of the engine to such 30 a degree as to permit a higher ratio of compression to be employed without the danger of pre-igniting the compressed gases.

A still further object of my invention is to 35 effect an internal cooling of the cylinders of an internal combustion engine during alternate cycles of the engine by introducing a charge of air into said cylinders during alternate cycles of the engine.

40 And still a further object of my invention is to effect an efficient internal cooling of the cylinders of an internal combustion engine by constructing an engine having a plurality of cylinders arranged in pairs and providing means for alternately introducing a charge of air first in one 45 cylinder and then in the other cylinder, means being further provided for effecting a transfer of heat from the air in one cylinder from the other cylinder associated therewith containing 50 the products of combustion.

For a more detailed understanding of my invention, reference may be had to the accompanying drawing, which illustrates one form which my invention may assume, and in which:

55 Fig. 1 is a plan view, somewhat diagrammatic,

of an internal combustion engine and showing the intake and exhaust valve arrangement of a pair of associated cylinders, and

Fig. 2 is a vertical sectional view of an internal combustion engine constructed in accordance with my invention, and taken substantially on the line 2—2 of Fig. 1.

Referring more particularly to the drawing illustrating a preferred form of structure embodying the principle of my invention, 10 designates an engine block provided with a plurality of cylinders 11 enclosed within suitable jackets 12 in which a cooling medium is circulated for effecting an external cooling of the engine cylinders. Preferably these cylinders are arranged in pairs, the cylinders in each pair being placed in communication with each other by a passageway 13 preferably cast within the cylinder head 14 and connecting the combustion chambers 15 associated with each cylinder.

15 A rocker arm housing 50 is preferably secured on top of the cylinder head for housing the rocker arms 16 which are operatively connected with exhaust and intake valves 17 and 18 respectively. The exhaust and intake valves are arranged as shown diagrammatically in Fig. 1. A description of the structure and operation of one pair of cylinders will suffice, since all pairs are similarly constructed and operated. The intake valves 18 are actuated to open and close simultaneously.

20 As shown in the illustrated embodiment of my invention, I have provided a manifold 19 containing a combustion fluid and an air manifold 20, the cylinder head being provided with a pair of passages 21 for connecting the said manifolds with the cylinders. A rotary valve 22 controls the flow of the combustible fluid or air into these passages 21 and the valves 17 and 18 are operated in timed relation with the valve 22 by means of the camshaft 16^a which actuates the rocker arms 16 to simultaneously actuate the intake and exhaust valves on the usual four stroke cycle. The rotary valve 22 preferably operates at one-eighth crankshaft speed, and any suitable driving connection may be employed. One suitable driving means is shown in Fig. 1, a gear 5 on the cam shaft 16^a drives a gear 6 on the valve shaft 22, the ratio between the valve shaft 22 and cam shaft being 4 to 1 since the cam shaft 105 is driven at one-half crankshaft speed. Fig. 2 illustrates an engine that is beginning its intake stroke with the pistons 23 going down and the intake valves 18 open. One of the cylinders is drawing a charge of the combustible fluid such

as the usual fuel mixture from the manifold 19, while the other cylinder is drawing a charge of air from the air manifold 20. The valves 18 are closed during the compression stroke and preferably one piston is slightly advanced with respect to the other which may tend to intermix the combustible fluid and air charges to some extent that have been previously drawn into the respective cylinders, although the identity of these charges will be preserved for the most part. The pistons are operated in synchronism.

A spark plug 24 is provided for each cylinder as on every other firing stroke alternate cylinders contain a combustible fluid or fuel mixture to be fired. The heat generated by the combustion of the mixture in one cylinder is transferred to the air in the other cylinder, and the air heated thereby is expanded to do useful work. Thus a good bit of the heat which is ordinarily dissipated by external cooling is internally absorbed by the air. Obviously the ratio of heat conductivity from one cylinder to the other may be regulated by varying the size of the passage 13. Where other means, such as metals of high heat conductivity, are employed for conducting the heat from the products of combustion to the air in an adjoining cylinder, the amount of heat transferred may be controlled by varying the character of the heat conducting medium. However for various reasons I find it advisable to provide a passage between the cylinders because it permits a more efficient transfer of heat besides permitting a slight intermixing of the combustible mixture and air.

The expanded air and burnt gases are exhausted in the usual manner into the exhaust manifolds 25. The rotary valve 22 is preferably continuously operated and is positioned as shown by the dotted lines when the valves 18 are again opened in the next engine cycle. Instead of the gas or combustible mixture flowing to the cylinder on the left, it is conducted to the cylinder on the right while the air is conducted to the cylinder on the left. Thus the combustible mixture is alternately admitted to each of the cylinders and the air is correspondingly admitted alternately to the said cylinders, one cylinder receiving a charge of the combustible mixture while the other cylinder receives a charge of air. Thus an internal cooling of each of said cylinders is obtained during alternate cycles of the engine, said cylinders being alternately cooled.

Piston rods 30 connected with the pistons 23 of a cooperating pair of cylinders are each operatively connected on the same throw of the crankshaft 31. Thus the power generated in both cylinders is transmitted to the crankshaft.

My construction effects a periodic internal cooling of the cylinders, which supplements the usual external cooling means and consequently it is possible to effect an increased cooling of the engine, thereby making it possible to increase the compression ratio without the danger of pre-igniting the compressed gases.

It is the expansion ratio to compression ratio which is important for efficiency in an engine. Usually these engine factors are identical, but in my engine something approximating 2 to 1 is obtained, expansion taking place in two cylinders for a very small compression ratio. This engine can therefore be operated with high efficiency and good economy.

It will be noted that each cylinder operates on an eight-stroke cycle, one or the other of the cylinders being fired at every fourth stroke of

the pistons. Said pistons are preferably operatively connected with the crankshaft 31 by the connecting rods 30 that may be articulated if so desired.

Although I have illustrated but one form of my invention and have described in detail but a single application thereof, it will be apparent to those skilled in the art to which my invention pertains, that various modifications and changes may be made therein without departing from the spirit of my invention or from the scope of the appended claims.

What I claim as my invention is:

1. In an internal combustion engine having fuel and air supply means, a pair of communicating working cylinders, pistons in said cylinders and operated in synchronism, fluid conducting means for connecting said fuel and air supply means to said cylinders, means for alternately placing said fluid conducting means in communication with said fuel and air supply means to alternately conduct fuel and air to said cylinders, and means for firing the charge of fuel in said cylinders. 90

2. In an internal combustion engine having fuel and air supply means, a pair of communicating cylinders, pistons in said cylinders and operated in synchronism, fluid conducting means for connecting said fuel and air supply means to said cylinders, valves intermediate the cylinder and fluid conducting means, means for actuating the valves, means operated in timed relation with said valve actuating means for alternately placing said fluid conducting means in communication with said fuel and air supply means and means for firing the charge of fuel in said cylinders. 100

3. In an internal combustion engine having fuel and air supply means, a pair of communicating cylinders, pistons in said cylinders and operated in synchronism, fluid conducting means for connecting said fuel and air supply means to said cylinders, valves intermediate the cylinder and fluid conducting means, means for actuating the valves, a second valve operated in time relation with said first mentioned valve actuating means for alternately placing said fluid conducting means in communication with said fuel and air supply means, and means for firing the charge of fuel in said cylinders. 110

4. In an internal combustion engine having a crankshaft, the combination of a pair of communicating working cylinders, pistons in said cylinders connected with said crankshaft and operated in synchronism, fuel supply means, air supply means, and means for alternately admitting a charge of air to said cylinders during alternate groups of four strokes of the engine for internally cooling each of said cylinders during alternate groups of four strokes of the engine. 125

5. In an internal combustion engine, the combination of a pair of communicating working cylinders, pistons in said cylinders and operated in synchronism, fuel supply means, air supply means, and means for alternately internally cooling each of said cylinders during alternate groups of four strokes of the engine. 135

6. In an internal combustion engine, the combination of a pair of cylinders, pistons in said cylinders and operated in synchronism, fuel supply means, air supply means, means for alternately admitting alternate charges of fuel and air in said cylinders, means for firing the charge of fuel in said cylinder, and means effecting internal cooling of said cylinders comprising means 140

150

- for effecting an alternate heat transfer between the products of combustion in one cylinder and the air in the other cylinder. 9. In an internal combustion engine, the combination of a pair of cylinders, pistons in said cylinders and operated in synchronism, fuel supply means, air supply means, means for alternately admitting alternate charges of fuel and air in said cylinders, means for firing the charge of fuel in said cylinder, and means effecting alternate internal cooling of said cylinders comprising means for alternately conducting the heat from the products of combustion in one cylinder to the air in the other cylinder. 80
7. In an internal combustion engine, the combination of a pair of cylinders, pistons in said cylinders and operated in synchronism, fuel supply means, air supply means, means for alternately admitting alternate charges of fuel and air in said cylinders, means for firing the charge of fuel in said cylinder, said engine provided with a passageway connected to the uppermost portion of said cylinders for alternately conducting the heat from the products of combustion in one cylinder to the air in the other cylinder to effect an internal cooling of each of said cylinders during alternate cycles of the engine. 85
10. An engine including a pair of communicating cooperating working cylinders, pistons operable in said cylinders, a common crankshaft operated by said pistons, and means cooperating with the cylinders and pistons for operating the pistons on an eight-stroke cycle, one of said cylinders operating four strokes in advance of the other. 90
15. 8. In an internal combustion engine, the combination of a pair of cylinders, pistons in said cylinders and operated in synchronism, fuel supply means, air supply means, means for alternately admitting alternate charges of fuel and air in said cylinders, means for firing the charge of fuel in said cylinder, said engine provided with a passageway connecting said cylinders for alternately conducting the heat from the products of combustion in one cylinder to the air in the other cylinder to effect an internal cooling of each of said cylinders during alternate cycles of the engine. 95
20. 11. An engine including a pair of communicating cooperating working cylinders, said cylinders each constructed to operate on an eight-stroke cycle, one of said cylinders operating four strokes in advance of the other. 100
